United States Patent Office.

JOSEPH REPETTI, OF PHILADELPHIA, PENNSYLVANIA.

Letters Patent No. 90,577, dated May 25, 1869

IMPROVED CAKE-MACHINE.

The Schedule referred to in these Letters Patent and-making part of the same.

Be it known that I, JOSEPH REPETTI, of Philadelphia, in the county of Philadelphia, and State of Pennsylvania, have invented certain new and useful Improvements in Machines for Making Cakes, &c.; and I do hereby declare that the following is a full, clear, and exact description of the construction and operation of the same, reference being had to the annexed drawings, making part of this specification, in which—

Figure 1 is a perspective view.

Figure 2, a section of the device which operates the plunger.

Figure 3 is a perspective view of the improved dough-box.

Figures 4 and 5 are sectional views of the pins or combs which are used for making annular cakes.

Figure 6 is an elevation of the improved cutter.

This invention relates to the improvement of that class of cake-machines in which the dough is put into a box, having a perforated bottom, the holes in said bottom corresponding to the shape which the cakes are intended to assume; and as the dough is forced through these holes by a plunger just fitting the box, a cutter underneath the bottom detaches the cakes at intervals.

The improvements consist in the combination and arrangement of the devices described.

The motive-power is applied to the pulleys *a* and *a'*, on the shaft *b*, *a* revolving loosely on the shaft, and *a'* being fastened thereto; hence, if the belt *o* runs on the pulley *a'*, the shaft *b* is revolved.

The belt *o* is guided by prongs *c c'*, on the rod *d*, which latter is bent thus the horizontal portions being supported by the frames *e e'*, and the vertical part running parallel with and behind the back frame *e'*.

Springs *f* or *f'* are provided, tending to push the rod always towards the left of fig. 1, and thus would move the belt on the loose pulley *a*, were it not for the stopper *g*, which bears against the arm *h*, on the rock-shaft *i*, as soon as the rod is pushed sufficiently to the right, to bring the belt *o* upon the fast or tight pulley, *a'*. Now, as the plunger *j*, screw *k*, and finger *l* reach their lowest points, the finger *l* depresses the short arm *h'*, on the rock-shaft *i*, causing the opposite arm, *h*, to rise and release the stopper *g*, when the springs for *f* will push the rod immediately to the left, thereby shifting the belt from the fast pulley *a'* to the loose pulley *a*, and consequently stopping the machine.

The upright shaft *m*, running in bearings *r* and *r'*, is driven by a quarter-turn belt *n*, running on the driving-pulley *p* on the shaft *b*, and the receiving-pulley *q* on the upright shaft. This shaft carries, underneath the bearing *r'*, a face-plate, *s*, to which the cutter *s'* is fastened.

Above the pulley *p* is fastened the eccentric *t*, which gives the usual intermittent motion of the apron *n'*, by means of the eccentric strap *t'*, levers *u* and *u'*, on the upright rock-shaft *w*, connecting-rod *v*, pawl-lever

v', and pawl *v''*, which latter drives the ratchet-wheel *w* on the shaft of the apron-roll *w*.

The descending motion of the plunger is obtained by means of the non-revolving screw *k*, nut *z*, fig. 2, ratchet-wheel 1, pawl 2, oscillating arm 3, and adjustable crank 4.

The crank works in the oscillating arm 3, imparting to the pawl 2, which is attached to the arm 3, an alternate circular motion. The pawl will, at its forward stroke, carry the nut *z*, by means of the ratchet-wheel 1, through an angular distance equal to its own amount of motion.

The screw *k*, being fastened into the plunger *j*, is, like the latter, kept from revolving by the parallel guides 5 5, on the dough-box 10; hence, it follows, that the intermittent revolving motion of the nut, causes in the screw a corresponding rectilinear motion, which in this instance is downward.

Whenever the pawl 2 is thrown out of gear with ratchet-wheel 1, it being provided for that purpose with a small handle, the plunger may be raised or lowered, at will, by means of bevel-wheels 7 and 8, and hand-wheel 9. If it is at the bottom of the box, it may be raised to permit the introduction of a new quantity of dough. The slide 6, fig. 3, having been brought previously underneath the bottom of the dough-box, the plunger is now depressed by turning the hand-wheel in the reverse direction until the dough forms a solid mass, then the pawl 2 is thrown into the teeth of the ratchet-wheel 1, and the machine started by pushing the knob *d* on the rod *d*, in, which will bring the belt *o* upon the fast pulley *a'*.

I do not confine myself to the use of "fast and loose" pulleys for stopping and starting the machine, for the same object may be obtained by means of plain or friction-clutches, which are too well known to require any descriptions. In that case, the sliding part of the clutch is connected with the rod *d*, the belt running always in the same plane.

The dough-box, fig. 3, has only three solid or continuous sides, the front side being closed by a hinged door, *y*, and the bottom, *y'*, being made movable, the latter rests on projections in the interior of the box, and is provided with V-slides to fit those of the slide 6. The "combs" *x*, for forming cakes with holes, are also made movable to facilitate cleaning. They rest in small grooves, and do not project above the surface of the bottom, so that all the material can be pressed out.

The positions of the upright shaft *m*, and the cutter *s'* on said shaft, are such, relative to the dough-box 10, that, as they revolve, the wire *s'* of the cutter will sweep past the lower surface of the bottom, *y'*, cutting off all the dough that has been forced through.

The construction of the cutter is shown in fig. 6, where *s'* is a metal frame, on which the wire *s'* is stretched. The shank *s''*, which is fastened to the frame by a small set-screw or other suitable means, supports

also one end of the wire. It will be evident, that by drawing s^3 outward, the wire is stretched to the required tension, the set-screw serving to keep the shank in that position.

The shank s^3 is provided with a hole, shown by dotted lines, for the purpose of receiving a bolt or screw, by which the whole is fastened to the lower side of the face-plate.

There have been removable bottoms used for dough-boxes, but they had to be lifted through the box, and my improvement consists in arranging the bottom, so that it can be slid out in front, which is much more convenient.

The apron n^2 , with its intermittent motion, the plunger j , counter-shaft b , and "fast and loose" pulleys, are old devices, and have been used in machines for making cakes; nor do I claim as my invention, the idea of putting pins, combs, or other devices into the perforations of the bottom of the dough-box, when the same are fastened with screws or otherwise; but

What I claim as my invention, and desire to secure by Letters Patent, is—

1. The combination of the automatic stopping-device, consisting of the finger l , rock-shaft i , arms h and h' , rod d , spring f , and stopper g , with the plunger j , screw k , and pulleys a and a' , or their equivalents, substantially as and for the purpose herein described.

2. The combination of the upright shaft m with the

projection r^2 , dough-box 10 , with its hinged and removable door 7 , plunger j , and screw k .

3. The combination of the revolving cutter s^1 with the dough-box 10 , substantially as and for the purpose set forth in this specification.

4. The combination of the single non-revolving screw k with the plunger j , ratchet-wheel 1 , pawl 2 , oscillating arm 3 , and adjustable crank 4 , substantially as specified.

5. The combination of the loose or removable pins or "combs" x , with the dough-box, substantially as and for the purpose specified.

6. The combination of the bevel-wheels 7 and 8 , and hand-wheel 9 , with the non-revolving screw k , revolving nut z , and plunger j , substantially as and for the purpose specified.

7. The combination of the slide 6 with the movable bottom y^2 and dough-box 10 , substantially as and for the purpose set forth in this specification.

8. The combination of the cutter, fig. 6, composed of the wire s^1 , frame s^2 , and shank s^3 , with a revolving shaft, m , substantially as herein specified.

In testimony whereof, I have signed my name, in presence of two subscribing witnesses, this day of March, 1869.
